UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

TUCK-GUIDE FOR SEWING-MACHINES.

1,176,595.

Specification of Letters Patent.

Patented Mar. 21, 1916.

Application filed December 10, 1908. Serial No. 466,862.

To all whom it may concern:

Be it known that I, LANSING ONDERDONK, a citizen of the United States, residing at New York city, in the county of New York, 5 State of New York, have invented certain new and useful Improvements in Tuck-Guides for Sewing-Machines; of which the following is a description, reference being had to the accompanying drawing and to 10 the letters and figures of reference marked thereon.

My invention relates to new and useful improvements in tucking guides for sewing machines, and has for an object to provide 15 a tucking guide which will be capable of forming a plurality of tucks simultaneously and directing the same to a plurality of needles whereby a series of tucks may be formed and stitched at one time.

20 A further object of the invention is to provide a tucking guide of the above character, which shall be simple in construction and in which the fabric to be tucked may be quickly inserted.

25 Further objects of the invention will in part be obvious and will in part be herein-after more fully described.

In the drawings which show by way of illustration one embodiment of the invention: 30 Figure 1 is a plan view of my improved tucking guide, showing the position of the same relative to a sewing machine. Fig. 2 is a side view of the same, certain parts of the machine being in section. Fig. 35 3 is a top plan view of the lower tuck forming member. Fig. 4 is a sectional view through the tucking guide, showing the manner of folding the fabric. Fig. 5 is a 40 sectional view on the line 5—5 Fig. 3, looking toward the bent over portions of the folding guides.

The sewing machine to which my tucking guide is shown attached, is of the multiple needle type. Said machine includes 45 a work support 1, a presser foot 2, which is provided with a plurality of needle holes 3, through which operate a plurality of needles carried by a needle bar 4, reciprocating in the overhanging arm 5 in the usual manner.

50 My improved tucking guide as herein shown, comprises upper and lower members. The lower member 6, is a flat plate which is adjustably secured to the work support of the machine as herein shown by a slot and

screw connection 7. Said plate 6 is provided with a central upwardly extending fin 8. Said fin is located substantially in the line of feed and at its forward end is provided with a laterally deflected overhanging folding portion 9. The fins 10, 10, are located on opposite sides of the fin 8, and are each provided with an overhanging portion 12, 12, similar to the overhanging portion 9.

The fins 10, 10, are substantially parallel 65 with the folding portion 9 at the end thereof, nearest the stitching point but said fins, a short distance from their front ends, diverge outwardly away from each other toward the front of the machine, as clearly 70 shown in Fig. 3.

The fins 11, 11, are similar to the fins 10, 10, and are provided with laterally deflected overhanging portions 12. The fins 11, 11, however, diverge at a greater angle relative 75 to the central fin 8, than the fins 10. Each of the folding fins above referred to, at their ends nearest the front of the machine, substantially merge into the supporting plate 6, and as you follow along said folding fins, 80 the height of the fin increases until the portion of the fin is reached where it is bent laterally to form the overhanging folding portion.

The upper member 13 of my improved 85 tucking guide, comprises a supporting bracket 14, which is secured to the head of the machine by suitable screws 15. Pivoted to the bracket 14 is an arm 16, which is secured to the bracket by the pivot bolt 17. 90 Said arm 16, carries a laterally projecting supporting member 18, which is secured to the arm 16, by suitable screws 19. A second member 20 is adjustably secured to the supporting member 18 by means of the slot 95 and screw connection 21. The supporting member 20 is provided with a plurality of spaced folding fingers 22. Said folding fingers 22, are so disposed on the support 20 as to lie substantially centrally between the 100 folding fins on the lower member of the tucking guide. Said folding fingers are also arranged so that they diverge toward the front of the machine in the same manner that the folding fins diverge. Each of the 105 folding fingers at their outer ends is connected so as to form a flat plate 23, which rests upon the material before the same passes on to the folding fins.

The inner edge of the plate 23, between 110

each of the guiding fingers 22 is curved, so as to allow the fabric as soon as it passes underneath the flat plate 23, to slide freely up on to the folding fin and thus start the 5 folding of a tuck.

- As the fabric passes over the folding fins and underneath the guiding fingers, the tucks will be gradually developed by reason of the fact that the guiding fingers approach 10 each other, giving up fabric to the formation of the tuck and by reason of the fact that the guiding fins increasing in height, take up the slack in the fabric which is given up by the folding fingers at its for- 15 ward end the guiding fin turns over the tuck which has been formed, and allows the same to pass properly underneath the presser foot 2, so that each of the folded tucks may be stitched and secured.
- 20 The position of the fabric in the tucking guide is clearly illustrated in Fig. 4. The forward end of each of the folding fingers 22 tapers downward so that said fingers may extend laterally deflected 25 portion of the folding fin and thus hold the tuck in its proper folded position, until the same passes underneath the presser foot.

The arm 16 which carries the upper member of the tucking guide is held in its various adjusted positions, by means of a 30 friction washer 24. The outer end of the arm 16 when the upper member of the tucking guide is lowered on to the fabric, engages a stop screw 25, carried by a lug 26 formed on the head of the machine. By 35 adjusting said stop screw, the position of the upper tuck forming member, relative to the work support may be varied. A spring latch 27 serves to hold the arm 16 against 40 the stop screw and locks the upper member of the tucking guide on the fabric.

In the operation of my device, the latch 27 is released and the upper member of the tuck forming guide is raised. The fabric 45 is then placed on the lower tuck forming member and the upper tuck forming member thrown down on to the fabric. As the upper member is brought into place, the fabric is folded around the folding fins and 50 may be readily pushed forward through the folder, so as to be engaged by the feed dog 28 of the sewing machine. As soon as the machine is started, the feed dog 28 will then draw the fabric through the tucking guide 55 and the folding fins together with the folding fingers, will operate to form the tucks and direct the same to the stitching mechanism. By loosening the screw connection 21, the entire upper member may be ad- 60 justed laterally relative to the lower member, and to the stitch forming mechanism. By loosening the screw connection 7, the lower member may be also laterally adjusted relative to the upper member, and to the 65 stitch forming mechanism. By these adjust-

ments, the size of the tuck being formed and stitched may be varied to a certain degree.

It will be noted that I have provided a tuck forming member which is very simple 70 in construction and by which a plurality of tucks may be simultaneously formed and stitched. The holding of the fabric out flat before the same passes to the folding members, enables the operator to properly 75 guide the fabric so as to form the tucks in the desired position and also facilitates in the proper forming of the series of tucks.

In Fig. 4 it will be noted that the overhanging portion 12 of the fins 8, 10 and 11, 80 extends over the folding fingers 22. The folding fingers 22 are however, carried by the arm 16, which is pivoted at a point almost directly above the overhanging portions 12, so that said folding fingers 22 will 85 swing in the arc of a circle, and move underneath the overhanging portions in a direction substantially parallel to the line of feed of the machine.

Having thus particularly described my invention, what I claim as new and desire to secure by Letters Patent, is:—

1. A tucking device comprising a primary series of laterally spaced tucking blades rigidly connected together at their bases, a 90 secondary series of oppositely directed tucking blades interposed between and alternating with those of the primary series, and means whereby the blades of one of said series may be withdrawn in a direction 95 lengthwise thereof from interlocking relation with the blades of the other series.

2. A tucking device comprising a primary series of laterally spaced tucking blades rigidly connected at their bases and provided with overhanging portions at their delivery ends, a secondary series of laterally spaced guiding blades respectively extending longitudinally between said tucking blades and under said overhanging portions thereof, and means whereby said guiding blades may be withdrawn longitudinally from interlocking relation with said tucking blades.

3. A tucking device comprising a primary series of laterally spaced tucking blades rigidly connected together at their bases, a secondary series of tucking blades interposed between and alternating with those of the primary series, and means whereby the blades of one of said series may be withdrawn in a direction lengthwise thereof from interlocking relation with the blades of the other series.

4. A tucking guide including in combination, upper and lower tuck forming members, said members being arranged and constructed to gradually fold simultaneously a plurality of tucks and direct the same to the stitch forming mechanism, and means connected to the front end of said upper mem- 120

bers and at the lower edges thereof for smoothing out the fabric in advance of the tuck forming members.

5. A tucking guide including in combination, upper and lower tuck forming members, said members being arranged and constructed to gradually fold simultaneously a plurality of tucks and direct the same to the stitch forming mechanism, and a plate carried by the front ends of the upper members, and flush with the lower face thereof, for engaging the upper face of the fabric in advance of the lower tucking members for smoothing out the fabric.

15 6. A tucking guide including in combination, a lower member, folding fins carried by said lower member over which the fabric passes, said folding fins having laterally projecting folding portions at their forward ends and at their upper edges, said folding fins gradually diverging from the folding portions toward the front of the machine, an upper member, guiding fingers carried thereby, said guiding fingers being located 25 on each side of said guiding fins and extending underneath the overhanging portion, whereby a plurality of tucks are formed and directed to the stitch forming mechanism and means for moving the upper member 30 in a direction lengthwise of the fingers for positioning said fingers underneath the laterally projecting portions of the fins.

7. A tucking guide including in combination, a lower member, tuck forming fins carried by said lower member over which the fabric passes, the forward end of said fins having laterally projecting overhanging portions at their upper edges for folding the tuck, said fins diverging from the overhanging portion toward the front of the machine, said fins increasing in height from the front of the machine toward the stitch forming mechanism, an upper member, guiding fingers carried thereby and located between the tuck forming fins, said guiding fingers projecting underneath the laterally projecting portions of the guiding fins and a flat plate connecting the outer ends of said guiding fingers for smoothing the fabric as it passes to the tucking guide.

8. A tucking guide including in combination, a lower plate, folding fins carried thereby over which the fabric passes, said folding fins converging toward the stitching point and having laterally projecting folding portions at their forward ends and at their upper edges, an upper member, a smoothing plate carried thereby for holding the fabric upon said lower plate, guiding fingers carried by said upper member, and coöperating with said folding fins to form a plurality of tucks.

9. The combination with stitch forming mechanism, of a tucking guide, including a lower member adjustable laterally relative

to the stitch forming mechanism, and having a plurality of vertical tuck forming fins, an upper member coöperating with said lower member and having vertical tuck forming fins, said fins being constructed and arranged for gradually forming a plurality of tucks and means whereby said upper member may be adjusted laterally relative to said stitch forming mechanism. 70

10. The combination with stitch forming mechanism, of a tucking guide including a lower member, an upper member, coöperating folding members carried by said upper and lower members for gradually forming a plurality of tucks and means for pivotally supporting said upper member, whereby the same may be moved in a direction toward and from the stitch forming mechanism and in a vertical plane parallel to the feed of the machine. 75

11. The combination with stitch forming mechanism, of a tucking guide, including a lower member, an upper member, coöperating folding members carried by said upper and lower members for gradually forming a plurality of tucks and means for pivotally supporting said upper member whereby the same may be moved in a direction toward and from the stitch forming mechanism, and in a vertical plane parallel to the line of feed of the machine for the insertion of the fabric, an adjustable stop for limiting the downward movement of said upper member and means for holding said upper member in its lowered position. 90

12. The combination with stitch forming mechanism, of a tucking guide, including a lower member, folding fins carried by said lower member over which the fabric passes, and having laterally projecting overhanging portions at their forward ends and at their upper edges, an upper member, folding fingers adapted to engage the fabric underneath said overhanging portions of the folding fins, means for pivotally supporting said upper member whereby said folding fingers may be moved longitudinally underneath the overhanging portions. 105

13. A tucking guide including in combination, upper and lower tuck-forming members for forming simultaneously a plurality of tucks, means for pivotally supporting said upper member, whereby the same may be moved in a direction substantially parallel with a central plane lengthwise of the tuck-forming members, said means including an arm, a bracket to which said arm is pivoted, and a friction washer for holding said arm in its various adjusted positions. 115

14. A tucking guide including in combination, upper and lower tuck-forming members for forming simultaneously a plurality of tucks, means for pivotally supporting said upper member, whereby the same may be moved in a direction substantially paral- 120 125 130

lel with a central plane lengthwise of the tuck-forming members, said means including an arm, a bracket to which said arm is pivoted, a friction washer for holding said arm in its various adjusted positions, an adjustable stop for limiting the downward movement of the upper member, and a spring latch for holding said upper member on the fabric.

13 15. A tuck guide including in combination a lower member, tuck forming fins carried by said lower member, the forward ends of said fins having laterally projecting overhanging portions at their upper edges for 15 folding the tucks, an upper member having guiding fingers coöperating with said tuck forming fins and means for supporting said upper member so that the same may be swung in a direction substantially parallel 20 with the line of feed for carrying said guiding fingers under the overhanging portions of said fins.

16. The combination with stitch forming mechanism, of a tucking guide including a 25 lower member, an upper member, coöperating folding members carried by said upper

and lower members for gradually forming a plurality of tucks and means for pivotally supporting said upper member, whereby the same may be moved away from the lower 30 member for the insertion of the fabric, said upper member being adjustably attached to its supporting means, whereby the same may be adjusted laterally.

17. The combination of stitch forming 35 mechanism, of a tucking guide including a lower member, a folding fin carried by said lower member, and having a laterally projecting overhanging member, a folding finger adapted to engage the fabric underneath 40 the overhanging portion of the folding fin, and means for pivotally supporting said upper member, whereby said folding finger may be moved in a longitudinal direction underneath the overhanging portion. 45

In testimony whereof I affix my signature in presence of two witnesses.

LANSING ONDERDONK.
